DESIGN FOR A HAMPER

Silas R. Horn, New York, N. Y.

Application May 7, 1941, Serial No. 100,826

Term of patent 7 years

To all whom it may concern:

Be it known that I, Silas R. Horn, a citizen of the United States and resident of New York city, in the county of New York, and State of New York, have invented a new, original, and ornamental Design for a Hamper, of which the following is a specification, reference being had to the accompanying drawing, forming a part thereof.

In the drawing:

Fig. 1 is a perspective view of a hamper with the cover in open position, showing my new design.

Fig. 2 is a side elevational view of the same.

Fig. 3 is a front elevational view of the same, illustrating the cover in closed position.

Fig. 4 is a top plan view of the same.

The dominant feature of the design resides in the specific design of hamper shown having the specific contour of its front face as shown. This contour comprises the combination of a convexed shaped vertical central portion continuing at its sides into a pair of concaved shaped vertical side portions terminating in vertical sharp edges which continue into a pair of rearwardly extending vertical beveled edge portions.

I claim:

The ornamental design for a hamper, as shown and described.

SILAS R. HORN.
